UNITED STATES PATENT OFFICE

RICHARD T. HOSKING, OF WILMETTE, ILLINOIS, ASSIGNOR TO H. R. HOUGH COMPANY, OF CHICAGO, ILLINOIS, A CORPORATION OF ILLINOIS

BATHING CAP

Application filed September 26, 1929. Serial No. 395,426.

This invention is an improvement in bathing caps. Its object is to provide a bathing cap with a pocket adapted to hold small articles such as a packet of paper matches, cigarettes, a dry handkerchief. The object of the pocket is to keep the articles dry while the bather is swimming or engaged in water sports, etc. Moreover, the articles are kept readily accessible without removing the cap from the head or without possibility of dripping water from the upper part of the cap into the pocket when the pocket is opened to put in or take out articles.

A still further object is to provide a stretchable elastic closure that can be pulled away from the cap proper to open the pocket and will close and remain water-tight when released.

With these objects in view the invention comprises the devices described and claimed and the equivalents thereof.

In the drawings Fig. 1 is a view showing the cap in use.

Fig. 2 is an enlarged side view of the cap wherein the pocket occupies the entire inside area of the cap.

Fig. 3 is a perspective view of the same, the elastic margin of the pocket pulled away from the cap band.

Fig. 4 is a front view of a cap formed with an exterior smaller pocket.

Fig. 5 is a part sectional view on the line 5—5 of Fig. 4.

Fig. 6 is a fragmentary side view of a modified form of pocket.

The cap proper is preferably an ordinary bathing cap 1 usually made of sheet rubber or other water-proof material and provided around its marginal edge with an elastic band, a drawing string or other suitable binding 2 adapted to bind the margin snugly around the head of the wearer in known manner.

My improvement is applied to a cap of the kind referred to by affixing to it a piece of rubber or fabric material having an elastic lower edge 3, 3a and shaped to define an inverted pocket 4 to receive articles 5, 5a, its sealed marginal edges 6, 6a preferably being secured to the cap by vulcanizing, cementing or otherwise, as in Figs. 1 to 5, although

the edges may be unattached, as in Fig. 6. The part 3, 3a of the lowermost margin, defining the opening or mouth of the pocket is left unsecured and is provided with a binding strip of elastic material whereby the pocket 55 mouth closes in clasping relation with the margin of the cap or with the head band, if the cap is provided with a head band. The flexible margin of the pocket keeps articles in the pocket and keeps water out. 60

The cap may be worn with the inverted elastic-mouthed pocket at the front, as indicated in Fig. 1, or it may be at the side, or in any other desired location.

The pocket may be small in comparison 65 with the size of the cap, as in Figs. 4 and 5, or it may include a large part of the area of the cap or even the whole of it, as shown in Figs. 2 and 3, without departing from my invention as set forth in the claims. 70

When the pocket is small, as in Fig. 4, it may be united to the external surface of the cap as in Figs. 4 and 5, or to its internal surface, or inside the cap and fastened to it by its mouth only, as in Fig. 6. When the pocket 75 is arranged to include the entire area of the cap, as in Fig. 2, it is preferably made by using two ordinary caps nested, their marginal edges secured together by cementing, vulcanizing or otherwise to provide a water-tight seam, a part of the marginal edge 3 being left unattached to provide the pocket mouth.

Each of the forms illustrated provides in conjunction with the bathing cap proper a 85 pocket that is inverted so as to shed water, elastic-mouthed to yieldingly clasp the head of the wearer so as to prevent entrance of water, and stretchable to permit the pocket to be pulled open for the insertion or removal of articles.

The contents of the pocket, if of soft material, such as a packet of cigarettes or a handkerchief, comprises a protecting pad for the wearer's head, reducing the liability of 95 injury, for example, while diving.

Having thus described my invention what I claim and desire to secure by Letters Patent is:

1. A bathing cap, an inverted pocket for

said cap comprising a second cap nested therein, the lower marginal portions of said caps secured together by water-tight seams excepting a portion that defines the mouth of the pocket, the marginal edge of the pocket orifice being of elastic material for the purposes set forth.

2. A bathing cap of waterproof material having a head band, a pocket piece united in inverted position to the cap by water-tight seams, the lower marginal portions of the pocket piece and cap overlapping and together defining a pocket opening, at least one of said marginal portions being of elastic material and arranged to be stretched into water-tight yielding engagement with the other marginal portion when the cap is in use, thereby defining an inverted pocket for the reception of articles, the opening of said pocket being normally held closed against the entrance of water.

In testimony whereof, I affix my signature:

RICHARD T. HOSKING.
